BOAT HULL WITH GLIDING POOP

Cosimo Centaro, Via Monterosa 35, Turin, Italy

Filed May 20, 1970, Ser. No. 23,070

Term of patent 14 years

Int. Cl. D12—06

U.S. Cl. D71—1

FIG.1

FIG.2

FIG.3

FIG.4

FIG. 1 is a plan of the boat hull with gliding poop of the invention;

FIG. 2 is a perspective view of the hull of FIG. 1;

FIG. 3 is an enlarged front elevation of the hull taken from the bow end of the boat;

FIG. 4 is an enlarged rear elevation of the hull taken from the poop end of the boat.

I claim:

The ornamental design for a boat hull with gliding poop, as shown and described.
